UNITED STATES PATENT OFFICE

2,545,630

JAW FACE FOR PIPE TONGS

James P. Ratigan, Los Angeles, Calif., assignor to
 J. P. Ratigan, Inc., Los Angeles, Calif., a corpora-
 tion of California

Application October 14, 1947, Serial No. 779,795

1 Claim. (Cl. 81—186)

1. My invention relates to pipe tongs or wrenches of the heavy-duty type, and has particular reference to an improved replaceable bit construction.

In my Patent No. 1,942,492, issued January 9, 1934, I disclose a pipe tongs wherein the teeth or bits are in the form of square tool stock adapted to be retained within the body portions of the tongs so that only one longitudinal edge of each bit projects for engagement with a pipe. The bits may be retained within broached slots in the tongs, and are arranged parallel to the axis of the pipe or other material to be worked upon. This patent also discloses a cast boss adjacent each slot, which boss may be threaded so that a nut may be threaded thereon to overlie the slot and thereby secure a bit in the respective slot.

My present invention utilizes this construction of my prior patent, but constitutes an improvement thereon in that it is not necessary to remove the nut from the threaded boss. Instead I employ a slotted nut that may be rotated to align the slotted portion with the bit so that the bit may be removed. After replacing the bit, the nut may be rotated tight against the associated portion of the tongs, at which position a solid portion of the nut will overlie the bit and retain it in the bit slot.

My present invention also incorporates a bit retaining slot that is open on both ends, compared to the single-ended slot of my prior patent. This double-ended construction permits speedier and more accurate broaching of the bit slots, and the bits are retained at the other end of the slot by means of a nut threaded onto a cast boss. This nut at the other end of the slot, however, may be solid inasmuch as the bits are preferably removed from one end only of the particular bit retaining slot.

It is therefore an object of my invention to provide an improved bit retaining construction for heavy-duty pipe tongs or wrenches.

Another object of my invention is to provide a slotted nut retainer for removable bits for pipe tongs.

A further object of my invention is to provide a bit retaining slot construction wherein the slot is open at both ends and which has associated therewith bit retaining mechanisms.

Other objects and advantages of my invention will be apparent in the following description and claim, considered together with the accompanying drawings, in which

Fig. 1 is an elevation view of a presently preferred embodiment of my invention as applied to a conventional pipe tongs used in the oil drilling industry;

2. Fig. 2 is an enlarged view of the head portion of the tongs of Fig. 1, but with portions broken away to show the internal construction;

Fig. 3 is a greatly enlarged view of the bit retaining construction on the body member of the tongs of Figs. 1 and 2; and

Fig. 4 is a greatly enlarged section taken along the line IV—IV of Fig. 2 and accordingly corresponding to Fig. 3.

Referring to Figs. 1 and 2, a pipe tongs 10 may include a body or handle member 11 that is enlarged at one end to form a head 12 that may be slotted as at 13 to receive a movable jaw 14 pivoted thereto by means of a pivot bolt 15. The jaw 14 is preferably curved so as to define a pipe receiving opening 16 defined by the jaw and also portions of the head 12.

The jaw 14 is preferably urged towards a closing position, and this function may be effected by a compression spring 17 pressing against an integral projecting lug 18 formed on the jaw 14, and the other end of the spring may be secured by means of an adjustable threaded plug 19 received within a spring bore 21. The closing movement of the jaw 14 may be limited by the engagement of the lug 18 with a bottom edge 22 of the jaw-receiving slot 13.

The handle 11 and the jaw 14 are preferably of cast construction, although they could be of forged construction. I find that steel castings are suitable for this purpose, and have the desired strength. In this connection it should be noted that the jaw 14 may be strengthened by the inclusion of a rib 23 on the inner curvature thereof, as well as by a widened tip portion 24 having a thickness substantially equal to the head member 12.

The pipe engaging teeth of the tongs may be in the form of removable bits 25 retained in squared slots 26 having one side thereof opening inwardly to the pipe receiving cavity 16. One such bit may be retained in the head portion 12, and another in the tip 24 of the jaw 14. While I have found that two such bits are sufficient, additional bits may be added if desired, particularly on the jaw 14.

The bit retaining structure of my invention is best illustrated in Figs. 3 and 4, and there it will be noted that bosses 27 may be formed at either end of the bit retaining slot 26 and may be threaded so as to receive a solid nut 28 on the lower boss, and a slotted nut 29 on the upper boss. I have found that cast bosses are ideally suited for this purpose, but if desired, bosses could be welded to the head 12 or to the jaw 14. These cast bosses are greatly superior

to studs inserted through drilled holes, inasmuch as there is no weakening of the head 12 or the tip 24 which would be critical due to the forces exerted upon the bit retaining slots 26. The bit retaining slots 26 are preferably open at each end so as to permit a broaching tool to be passed therethrough if necessary to accurately form the casting to receive the bits 25.

Referring particularly to Fig. 3, it will be noted that the slotted nut 29 may be tightened against a spot-faced portion 31 of the head 12 and likewise the tip 24 so that a very definite and tight contact with the body portion 12 may be obtained. Accordingly the nut 29 may be slotted as at 32 in a portion that will not overlie the bit 25 when the nut is tightened solidly against the body member 12. However by unthreading the nut 29 through a partial turn, the slot 32 may be disposed over the bit 25 to permit it to move out of its slot 26. The bit may then be removed and a new corner of the square bit positioned for pipe engagement, or if all four edges of the bit have already been dulled by use, a new bit 25 may be inserted. Thereafter the nut 29 may be rotated to its set position, whereupon a solid portion will overlie the bit 25 and retain it in its slot 26. In this connection it will be noted that the solid nut 28 at the other end of the slot 26 is generally permanently maintained on its threaded stud 27 for the sole purpose of closing off the other end of the slot 26. If desired, however, both nuts 29 and 28 could be slotted so as to make the bit removable from either end, although this is not ordinarily desirable or necessary.

My preferred method of assembly of the slotted nut 29 to the tongs is to thread the nut 29 while still in a normal or solid condition on its stud 27 until it bears securely against the spot-faced portion 31. This angular position of the nut with respect to the slot 26 is noted, and thereafter the nut is unthreaded from the stud and the slot 32 cut in the nut at a position that will not overlie the bit slot 26. In this way the precise placement of the slot 32 on the nut 29 may be effected.

While I have described my invention with respect to a specific embodiment thereof, I do not limit myself to this embodiment, nor otherwise, inasmuch as various modifications and changes could be made without departing from the true spirit and scope of my invention. Accordingly the disclosure is merely illustrative and not definitive of my invention.

I claim:

A pipe wrench comprising: a cast handle member including a slotted head portion; a cast jaw member pivoted to the handle member at the slot so as to define a pipe retaining cavity between the head portion and the jaw member; an angular slot disposed in the head portion and the jaw member and having an edge opening on the cavity and each slot having open ends; angular bits inserted in the slots and having an angular configuration corresponding to that of the slots so that an edge will project outwardly into the cavity; cast bosses formed adjacent each end of each cavity and having threads formed thereon; a solid nut threaded on the bosses at one end of each slot; and a slotted nut threaded on the bosses at the other end of each slot, whereby the slotted nut may be rotated to align its slot with the bit receiving slot and may be tightened on the boss to cause a solid portion to overlie the bit retaining slot so as to lock the bit therein.
